MYRON A. MOSHER, OF BUFFALO, NEW YORK.

COMBINATION-LOCK.

1,086,551.

Specification of Letters Patent.

Patented Feb. 10, 1914.

Application filed September 27, 1913. Serial No. 732,202.

To all whom it may concern:

Be it known that I, MYRON A. MOSHER, a citizen of the United States, residing at Buffalo, in the county of Erie and State of New York, have invented new and useful Improvements in Combination-Locks, of which the following is a specification.

This invention relates to a combination lock which is especially desirable for locking the gasolene supply valve of an automobile but which may be used in connection with various other parts to be locked. Its object is the production of a reliable lock of this kind which shall be simple and durable in construction and which can be manufactured at relatively small cost.

In the accompanying drawings: Figure 1 is a front elevation of the lock. Fig. 2 is a horizontal section on line 2—2, Fig. 1. Fig. 3 is an inverted horizontal section showing the locking bolt, its guide and its operating parts. Fig. 4 is a fragmentary transverse section on line 4—4, Fig. 2. Fig. 5 is a longitudinal section of the bolt-operating screw. Fig. 6 is a plan view thereof. Fig. 7 is a view of the rear end of said screw. Fig. 8 is a section on line 8—8, Fig. 2. Fig. 9 is a side elevation of the locking bolt.

Similar characters of reference indicate corresponding parts throughout the several views.

In the drawings the lock is shown in connection with a gasolene supply valve 1 located in the pipe leading from the gasolene tank to the carburetor of an automobile, the part to be locked against rotation being the rotary valve-stem 2. The latter passes transversely through the lock-case 3 and is provided on the front side of the case with a crank 4 or other suitable means for turning it. In the example illustrated in the drawings, the stem is provided within the lock-case with a fixed collar or disk 5 having a locking aperture 6 adapted to receive a locking bolt 7 arranged lengthwise of the valve stem. This bolt slides in a suitable guide 8 carried by a bracket 9 secured to the front wall of the lock-case. The bolt is constantly urged toward the collar 5 by a spring 10 secured to a bracket 11 projecting from a wall of the lock-case. The free end of said spring bears against a lip or projection 12 at the rear end of the locking bolt, as shown in Fig. 3. The locking bolt is withdrawn from the apertured collar 5 by a lever 13 pivoted between its ends to the bracket 11

and adapted to engage the front side of the bolt-lip 12. At its opposite end said lever carries a pin 14 which traverses the groove of a rotary screw or threaded shaft 15, the stem 15^a of which extends through the front wall of the lock-case and has a knob for turning it. The lever-arm carrying the pin 14 may be pressed against the screw by a suitable spring 16, as shown in Figs. 3 and 4. This construction insures the close engagement of the lever-pin with the screw, while allowing the lever to be pivoted with sufficient looseness to work freely at all times. This screw is suitably held against endwise movement in the case, the means shown in the drawings consisting of a shoulder 17 on the screw bearing against the inner side of the front wall of the case and a numbered dial 18 carried by the stem 15^a and bearing against the outer side of said wall. The thread of the screw 15 trends in the same direction from end to end and is provided at different points or intervals with return-channels 19 through which the lever-pin 14 may pass from one winding of the screw to the next, these channels being preferably oblique and trending reversely to the main groove of the screw, as shown.

Located at one or more points in the main channel or groove of the screw are baffles, cams or deflectors 20 and 21 adapted to be encountered by the lever pin 14 and constructed and arranged to direct said pin through one of the return channels into a preceding winding of the main groove and thereby baffle any attempt to unlock the bolt unless the screw is manipulated according to the predetermined combination of the lock. Each of these baffles is located in front of or adjacent to one of the return channels and trends toward the same, so as to direct the lever-pin toward its entrance. In order to allow the lever pin 14 to pass around the ends of the baffles, the adjacent sides of the screw thread are recessed or cut away, as shown at 22.

When the lever 13 is in the position shown, its left hand end is out of contact with the lip 12 of the locking bolt 7, allowing the spring 10 to push the bolt into the opening of the collar 5 and locking the valve stem 2. In order to withdraw the bolt, the lever must be swung a sufficient distance to engage the bolt-lip 12 and shift the bolt. If the screw had an ordinary continuous thread and no baffles, the lever could obvi-

ously be swung to the requisite extent by simply turning the screw forwardly without reversal, but the baffles 20 and 21 and return channels 19 require the rotation of the screw to be reversed to avoid entering said channels and permit the lever to continue its unlocking movement.

Assuming the bolt to be locked and the lever-pin 14 to be in engagement with the rear portion of the screw, as shown, in order to unlock the bolt, the screw must be manipulated as follows: It is first turned forwardly which causes the lever-pin 14 to follow the screw threads and approach the knob of the screw, the opposite end of the lever moving in the reverse direction and approaching the lip 12 of the bolt. By the continued forward rotation of the screw, the lever-pin advances thereon until it encounters the rear cam or baffle 20 which deflects the pin rearwardly toward the entrance of the companion return channel 19, and if this forward movement of the screw were then continued, the pin would be deflected rearwardly through said channel by its oblique walls back into the preceding turn or groove of the screw thread, thus causing the lever to recede from the lip of the locking bolt, or in other words, move in the wrong direction to unlock the bolt. To avoid such return movement of the lever-pin, the screw, after the pin has cleared the rear end of said baffle and before arriving at the entrance of said channel, as shown by full lines in Fig. 6, must be rotated backward a short distance to bring the reverse side of said baffle behind the pin and deflect it away from said entrance and in line with the main groove of the screw, as shown by dotted lines in Fig. 6. Upon now again reversing the screw or turning it forwardly, the lever-pin is caused to advance on the screw until it encounters the next baffle 21, when the rotation of the screw must again be temporarily reversed as above described, these operations being repeated for each baffle until the pin has advanced far enough to cause the lever to withdraw the locking bolt from the collar 5, when the valve-stem 50 will be unlocked. The proper extent of these forward and reverse movements of the screw is determined by the numbers of the dial 18 corresponding to the position of the baffles and return channels, as in ordinary combination locks.

It will be seen from the foregoing that unless the screw is reversed and again turned forward at the proper points, the lever-pin will retreat instead of advancing on the screw, thus effectively baffling any attempt to throw the locking bolt without knowledge of the proper combination.

To insure the return of the lever-pin through the channels 19, unless the screw is properly manipulated, the leading wall of

each channel is cut away at its front end to recede behind the trailing wall of the channel, as shown at 23 in Fig. 6, while the rear end of the companion baffle 20 or 21 extends rearwardly beyond said trailing or salient 70 wall.

To permit a ready change of the lock-combination, the body-portion 15 of the screw is preferably in the form of a cylindrical shell or externally-threaded sleeve 75 which is adjustable circumferentially on its core or stem 15^a, so that it may be turned more or less relatively to the dial 18 to change the combination of numbers necessary to throw the bolt. In the preferred 80 construction shown, said stem is provided at its rear end with a removable transverse retaining pin 24 which engages either of a pair of intersecting grooves 25 in the adjacent end of the screw-body, as seen in Figs. 85 5 and 7.

To allow the withdrawn bolt to resume its forward or locking position under the pressure of the spring 10, it is only necessary to turn the screw backward continuously, 90 which movement causes the lever-pin 14 to recede to the rear end of the screw, withdrawing the lever from the lip 12 of the bolt. The thread of the screw is provided at or near its rear end with a stop 25 to prevent 95 the lever-pin from leaving the screw.

In addition to the return channels 19 cooperating with the baffles 20 and 21, the screw is provided near its front and rear ends with supplemental return channels 26 and 27 100 unassociated with such baffles, these last-named channels allowing the lever-pin to pass back and forth from the endmost windings to the adjacent windings of the screw and thus permitting free rotation of the 105 screw at all times.

In some cases a single baffle and a single return channel may be employed, if desired, but a plurality of them is preferably used, as shown. 110

I claim as my invention:

1. The combination of locking-means, a rotary screw, and a member traversing said screw and controlling said locking means, said screw having a return channel connecting different windings of its groove and a baffle arranged in said groove adjacent to said return channel. 115

2. The combination of locking means, a rotary screw, and a member traversing said screw and controlling said locking means, said screw having its thread intersected by a return channel connecting adjacent windings of its groove and trending in the reverse direction to the thread, and a baffle arranged in said groove adjacent to said channel. 120

3. The combination of locking means, a rotary screw, and a member traversing said screw and controlling said locking means, 125

said screw having a return channel connecting adjacent windings of its groove and trending in the reverse direction to said groove, and a cam arranged in said groove adjacent to said return channel and trending substantially in the same direction as said channel.

4. The combination of locking means, a rotary screw, and a member traversing said screw and controlling said locking means, said screw having a return-channel connecting different windings of its groove and a baffle extending obliquely across said groove adjacent to said channel, the portions of 10 the screw-threads opposite the ends of the baffle being recessed to form passages for said controlling member.

5. The combination of locking means, a rotary screw, and a member traversing said screw and controlling said locking means, the thread of said screw trending in the same direction from end to end and being interrupted at one or more points by return channels trending reversely to said thread 20 and connecting adjacent windings of the groove formed by the thread, and oblique baffles arranged in said groove adjacent to said channels.

6. The combination of locking means, a 30 rotary screw, and a member traversing said screw and controlling said locking means,

said screw having a return channel connecting different windings of its groove and a baffle arranged in said groove adjacent to said channel, that wall of the channel nearest 35 the baffle stopping short of the opposite wall thereof.

7. The combination of locking means, a rotary screw, and a member traversing said screw and controlling said locking means, 40 said screw having a return channel connecting different windings of its groove and a cam extending obliquely across said groove adjacent to said channel, the walls of the groove being recessed opposite the ends of 45 the baffle to form passages for said controlling member, and the leading wall of said channel being arranged to recede behind the opposite wall thereof.

8. In a lock, the combination of a rotary 50 stem having a removable locking pin, an externally screw threaded sleeve rotatably mounted on said stem and provided at its rear end with locking recesses adapted to receive said pin, and a lock-controlling member traversing said threaded sleeve.

Witness my hand this 23d day of July, 1913.

MYRON A. MOSHER.
